(57) **CLAIM**

The ornamental design for a set-top box, as shown and described.

DESCRIPTION

1. Set-top box
- 1.1 : Perspective
- 1.2 : Rear perspective
- 1.3 : Front
- 1.4 : Back
- 1.5 : Left
- 1.6 : Right
- 1.7 : Top
- 1.8 : Bottom
- 1.9 : Reference
- 1.10 : Reference
- 1.11 : Reference
- 1.12 : Reference
- 1.13 : Reference

The claimed design is a set-top box for video conference or remote medical service; reproductions 1.9 and 1.10 are reference views showing the state that the claimed design is used as a standing type; reproduction 1.11 is a reference view showing the state of the stand adjusted in order for the claimed design to be mounted on the upper part of the display; reproductions 1.12 and 1.13 are reference views showing the state that the claimed design is mounted on a display device; reproductions 1.9, 1.11 and 1.12 are shown with the front obround panel in an alternate position for use; the large dashed broken lines seen in reproductions 1.12 and 1.13 showing the display device depict environmental subject matter only and form no part of the claim, while all other

(Continued)

broken lines in the reproductions depict portions of the set-top box that form no part of the claimed design.

1 Claim, 13 Drawing Sheets
